UNITED STATES PATENT OFFICE

LEMMA B. DACUS, OF SOCIAL CIRCLE, GEORGIA

SANITARY HOLDER

Application filed May 5, 1931. Serial No. 535,249.

This invention relates to holders, and more particularly to a sanitary holder for use in removably securing a napkin on a glass or tumbler.

An object of this invention is to provide an exceedingly simple holder which may be readily disposed about a glass or tumbler so as to firmly hold a paper napkin about the glass so that no foreign objects will enter the glass and so that the napkin will not be blown away.

Another object of this invention is to provide a simple device of this kind which may be used in serving of drinks or the like at a roadside wherein foreign objects will not be permitted to enter the glass while it is being carried to the purchaser thereof.

The above and various other objects and advantages of this invention will in part be described in and in part be understood from the following detailed description of the present preferred embodiment, the same being illustrated in the accompanying drawings, wherein:—

Figure 1 is a detail side elevation of a device constructed according to the preferred embodiment of this invention,

Figure 2 is a vertical section partly in detail of the device showing in dotted lines a modified form of the holder, and

Figure 3 is a side elevation of the device as applied to an irregular shape vessel.

Referring to the drawings wherein like numerals of reference designate corresponding parts throughout the several views, the numeral 10 designates generally a tumbler or glass of conventional construction which is used for holding liquids, and the numeral 11 designates a napkin of either paper or fabric construction which is disposed about the open end of the tumbler 10, this napkin 11 being securely held in position about the periphery of the tumbler 10 by means of a resilient holder, generally designated as 12.

This holder 12 comprises a pair of spring or resilient members 14 which are secured together intermediate the ends thereof by means of a securing member 15 which is preferably extended upwardly from the spring members 14, as at 16, so as to provide a han-

dle or means for placing or removing the holder from a tumbler. These spring members 14 comprise an upper horizontal portion 13, the ends of which are arcuately bent, as at 17, the curved portions 17 being continued downwardly and inwardly, as at 18, so as to clamp the napkin 11 about the periphery of the tumbler or glass 10. The extensions 18 are continued downwardly and outwardly, as at 19, so as to provide outwardly flared leg portions which facilitate the positioning of the holder on a glass.

As disclosed in dotted lines in Figure 2 at 19', the leg portions 19 may be continued downwardly so as to terminate substantially flush with the bottom of the tumbler 10. These straps or springs 14 are secured together in crossed relation to each other so that four clamping arms are provided from the two crossed spring sections which will hold the handle 16 concentrically of the tumbler 10.

In the operation of this device, the napkin 10 is preferably folded downwardly about the periphery or outer surface of the tumbler 10, and the handle 16 of the napkin holder may be grasped in the hand and the device moved downwardly over the upper end of the tumbler 10, the flared portions 19 or 19' operating to spread the spring members 14 so that the napkin will be firmly clamped against the outer surface of the tumbler 10.

In the modification of this invention shown in dotted lines in Figure 2, the lower ends of the clamping members 14 serve as an extension of the bottom of the tumbler 10 and prevent tilting or turning over of the tumbler as it is being carried on a tray.

It will be obvious, from the foregoing, that the holder herein disclosed will not only firmly hold a napkin or cover on a tumbler or glass, but will also aid in preventing the spilling of the contents of the glass by preventing the turning over of the glass.

It is, of course, understood that various changes and modifications may be made in the details of construction and design of the above specifically described embodiment of this invention without departing from the spirit thereof, such changes and modifications

being restricted only by the scope of the following claims.

I claim:—

1. As a new article of manufacture, a holder of the character described adapted to removably engage a glass tumbler for removably holding an article across the open end of the tumbler, comprising a pair of U-shaped resilient arms having the free ends thereof outwardly flared, and means for securing the closed portion of the arms together in intersecting relation.
2. As a new article of manufacture, a holder of the character described adapted to removably engage a glass tumbler for removably holding an article across the open end of the tumbler, comprising a pair of U-shaped resilient arms having the free ends thereof outwardly flared, and means for securing the closed portion of the arms together in intersecting relation, and a handle integrally formed with the securing means and disposed outwardly of the closed end of the arms.
3. In testimony whereof I hereunto affix my signature.

LEMMA B. DACUS.
